NEEDLE FOR PLATING KNIT FABRIC

Harry N. Sheppard, Maplewood, N. J., assignor
to Scott & Williams, Incorporated, New York,
N. Y., a corporation of Massachusetts

Application June 5, 1937, Serial No. 146,680

3 Claims. (Cl. 66—121)

This invention relates to circular knitting machines and more particularly to circular knitting machines arranged to knit a wrap or embroidery yarn on selected ones of needles knitting a fabric of a single yarn or of a plurality of yarns in plating relation to form an embroidery pattern plated on the face of the fabric, and it is an object of this invention to provide an improved method of plating to insure the desired yarn being on the outside of the fabric and it is a further object of this invention to provide a needle of improved construction for carrying out the improved method of plating.

In the drawing in which only such parts of a circular knitting machine are shown as are necessary to illustrate an application of the invention;

Fig. 1 is a view in elevation of a portion of a latch guard ring at the throat plate of a Scott and Williams circular knitting machine equipped for knitting wrap or embroidery strips upon a knit plated fabric, the view being developed in the plane of the paper;

Fig. 2 is a top plan view of the throat plate of the structure shown in Fig. 1, the parts being positioned as in a machine;

Figs. 3, 4 and 5 are views drawn to a larger scale and showing, in elevation, the hook of a preferred form of latch needle and its relation to the various yarns used in knitting the fabric, at three positions in the movement of the needle, after taking the yarns; to the position of the needle at which the relations of the yarns in the knitted loop is definitely determined;

Fig. 6 is a view in elevation, drawn to the same scale as Figs. 3 to 5 of the hook of a modified form of a needle in accordance with this invention, and

Fig. 7 is an enlarged transverse sectional view through the notched portion of the needle illustrating the manner in which the notch is deformed to provide substantially the same cross-sectional area and strength at the notch as elsewhere in the hook portion of the needle.

In the drawing the knitting machine to which the invention is applied is shown as a Scott and Williams circular knitting machine, such as is shown in the patent to Page and Swinglehurst, No. 1,906,204, dated April 25, 1933. As shown, the yarn fingers F^1 , F^2 feed the body and facing yarns b and f , respectively, in plating relation to all the needles n at the throat plate of the latch guard ring 550 while the wrap yarn fingers 767 feed the wrap or embroidery yarns w to the selected needles n^1 in advance of the throat plate.

In the operation of knitting machines of the

type disclosed difficulty has been encountered in insuring that the wrap or embroidery yarns w , which are fed to the selected needles n^1 by the wrap yarn finger 767, would maintain a position on the selected needles when the body and facing yarns b and f , respectively, are fed to the selected needles by the yarn fingers F^1 and F^2 , respectively, such that the wrap yarns would be found on the face of the fabric when the loops on the selected needles were cast off and knit as the wrap yarn w and the facing yarn f tended to be transposed as to position and to bring the facing yarn to the face of the fabric at the pattern in place of the wrapping yarn. This displacing of the wrapping yarn also occurred when the body of the fabric was knit of a single body yarn.

In order to insure the wrap yarn w being properly positioned the needles are provided with hooks shaped preferably as in Figs. 3, 4 and 5, and which extend outwardly and upwardly at a slight angle, as at 1, from the shank 2 towards the reversely extending portion forming the point 3. There is also provided a notch at the upper end of the shank 2 the face 4 of which merges into the inner face 5 of the portion 1 of the hook. The notch 4 may, as shown in Fig. 6, meet the inner face 5 of the top 1 of the hook at an angle, but in both constructions the notch provides a place in which the wrap yarn w may lodge, as shown in Figs. 4 and 5, while the plating or facing yarn f , which engages the needle shank 2 below the wrap yarn w as shown in Fig. 3 brushes or slides over the wrap yarn as the needles are drawn down to cast off their loops so that the yarns assume the proper positions as shown in Fig. 5.

In both constructions, it will be noted, the inner face 5 of the top 1 of the hook extends from the shank 2 at a small angle to the horizontal so there is little or no tendency for the yarn w in the notch to travel on the face 5 of the hook and the face 4 of the notch and face 5 of the top 1 of the hook meet in such a way that there is insufficient angle between them to cause the facing yarn f , as it slides over the wrapping yarn, to slide into or be held in the notch with the wrapping yarn w . The body yarn b , when fed from a yarn finger positioned as shown in Fig. 1, engages the needle hook away from the shank 2, as shown in Fig. 3, so there is little or no tendency for the body yarn b to be transposed with respect to either the facing or wrapping yarn. Where the fabric is knit of but a single body yarn the yarn is usually fed from the yarn finger F^2 , shown in the drawing, as feeding the facing yarn

to the needles, and the displacement of the body and wrap yarns has occurred. Where the wrap yarn *w* is taken by alternate needles of a group to interlace the wrap yarn with the needles of the group the movement of the wrap yarn into the notches 4 of the needles taking the yarn positions the wrap yarn further towards the back of the needles than formerly and renders the movement of the wrap yarn in back of the remaining needles of the group much easier and less liable to improperly position the wrap yarn with respect to other yarns taken by the wrapped needles.

In the manufacture of the needle the notch is formed by applying a die under pressure to the needle blank before the hook is bent to shape so the needle is substantially of the same strength and cross-sectional area in the region of the notch as a needle without the notch and there is no tendency, either because of the shape of the notch or because of a reduction in the amount of metal at the notch, for the needle to break at the notch. Fig. 7 of the accompanying drawing illustrate the manner in which the notch is die-formed to provide substantially the same cross-sectional area and strength at the notch as elsewhere in the hook portion of the needle.

In the claims wherever reference is made to a body yarn, it is intended such term shall also include the facing yarn where the fabric is knit of a plurality of yarns in plating relation as well as the body yarn where the fabric is knit of but a single yarn.

The method of plating described is not claimed herein as it is claimed in the divisional application Serial No. 206,048, filed May 4, 1938.

What is claimed is:

1. A needle having a hook with the inner surface upwardly and outwardly inclined from the needle shank and a notch at the junction of said inner surface and shank to retain one yarn while another yarn is passed over the first yarn to a position against said inner surface, said needle having substantially the same cross-sectional area and strength at the notch as elsewhere in the hook. 5

10 15 20 25

2. A latch needle having a yarn retaining notch at the junction of the inner faces of the shank and hook, said notch being arranged to retain a plating yarn to properly position said yarn with the remaining yarn in the knitted loop, said needle having substantially the same cross-sectional area and strength at the notch as elsewhere in the hook.

3. A needle having the inner face of the upper portion of the hook a flat surface inclined to the axis of the needle shank and a notch at the junction of the inner face and shank to retain one yarn while a second yarn is passed over said first yarn to engage said flat surface, the face of said notch merging into said inner face of the upper portion of the hook, said needle having substantially the same cross-sectional area and strength at the notch as elsewhere in the hook. 30
